UNITED STATES PATENT OFFICE.

FRANK BUCHANAN, OF SYRACUSE, NEW YORK.

MOUNTING FOR HEADLIGHTS.

1,383,386.

Specification of Letters Patent.

Patented July 5, 1921.

Application filed August 27, 1919. Serial No. 320,083.

To all whom it may concern:

Be it known that I, FRANK BUCHANAN, a citizen of the United States, and a resident of Syracuse, in the county of Onondaga and State of New York, have invented a certain new and useful Mounting for Headlights, of which the following is a specification.

This invention relates to headlights and has for its object a particularly simple and efficient construction whereby the headlight is yieldingly supported and relieved of shocks and jars incidental to its use on the railway car. The invention consists in the novel features and in the combinations and constructions hereinafter set forth and claimed.

In describing this invention, reference is had to the accompanying drawings in which like characters designate corresponding parts 20 in all the views.

Figures 1, 2, 3 and 4 are respectively, front and rear elevations, a plan view and a side elevation of a headlight embodying my invention.

25 This mounting for headlights comprises generally, a base, a body mounted on the base and spring means supporting the body on the base and acting to yieldingly permit a slight fore and aft movement of the body. 30 1 designates the base which may be of any suitable form, size and construction, it being here shown as in the form of a frame having openings 2 by means of which it is mounted on a suitable support.

35 3 is the body which is larger at its front end than at its rear, it conforming to the general outline of a parabolic reflector.

40 4 is a door at the front end of the body which door supports a suitable lens and also 45 a protecting grating 5 for the lens. The door is held in position in any suitable manner.

The base 1 is here shown as provided with a plurality of spaced apart posts 6 which are 50 pivotally connected at 6' to the base so as to swing fore and aft, these posts 6 being connected to the body 3 to yieldingly support the body so that the body floats when the vehicle on which the headlight is mounted is subjected to sudden jars as when the car is suddenly stopped or making a coupling.

In the illustrated form of my invention, the front posts are spaced apart a greater distance than the rear posts which are lo-

cated on opposite sides of the rear or narrow end of the body 3.

The body is formed with a laterally extending flange 7 having eyes or perforations for receiving the posts 6.

9 are springs encircling the posts 6 between the flange and the base, and 10 are additional springs encircling the posts 6 between the upper face of the flange 7 and heads as nuts 11 threading on the upper ends of the posts 6, the springs acting in opposition to each other.

Owing to the arrangement of the springs and the use of springs acting in opposition to each other, the headlight is relieved of all the jars received by the car body and is 70 floatingly supported on the base 1.

In headlights using incandescent lamps, the filaments are very readily broken by the jars the lamps are subjected especially when used on locomotives and engines such as are 75 used in mines to haul and shift cars where the lamp is subjected to heavy and sudden jars and as when coupling and uncoupling cars and starting and stopping. Oftentimes the filament lasts but a few hours.

By my headlight mounting the filament is relieved of the greater part of the shocks and the lamps last the normal life of incandescent lamps.

What I claim is:

1. A mounting for headlights comprising a base having a plurality of upright posts pivoted thereto and connected to the body, and spring means supporting the body and arranged to yieldingly resist pivotal movement of the posts, substantially as and for the purpose specified.

2. A mounting for headlights comprising a base having a plurality of upright posts, the posts being pivoted to the base, a body having vertical openings through which the posts extend, and springs interposed between the body and the base, substantially as and for the purpose set forth.

3. A mounting for headlights comprising a base having a plurality of upright posts, the posts being pivoted to the base, a body having vertical openings through which the posts extend, compression springs interposed between the body and the base and compression springs interposed between the body and the upper ends of the posts, substantially as and for the purpose described,

4. A mounting for headlights comprising a base, a plurality of upright posts pivoted to the base, a headlight having a laterally extending flange intermediate of its top and bottom and formed with openings through which the posts extend, springs encircling the posts between the base and the flange, springs encircling the posts above the flange

and heads on the posts against which the latter springs thrust, substantially as and for the purpose described. 10

In testimony whereof, I have hereunto signed my name, at Syracuse, in the county of Onondaga, and State of New York, this 30th day of June, 1919.

FRANK BUCHANAN
